TOOL AND JIG FOR CABLE WORK

Filed Jan. 21, 1929

FIG. 2

FIG. 1

INVENTOR
CHARLES ANDREW BAY
BY *Eilers & Schramburg*,
ATTORNEYS

UNITED STATES PATENT OFFICE

CHARLES ANDREW BAY, OF MORRISTOWN, NEW JERSEY, ASSIGNOR TO JAMES R. KEARNEY CORPORATION, OF ST. LOUIS, MISSOURI, A CORPORATION OF MISSOURI

TOOL AND JIG FOR CABLE WORK

Application filed January 21, 1929. Serial No. 333,877.

This invention relates to improvements in jigs, tools and the like, and particularly to an improved instrument adapted to be used in the preparation of lead sheath cable ends for service connections.

An object of the present invention is to provide an improved tool, which, in use, enables an accurate advance determination of the necessary sheath or insulation removal, preparatory to insertion of the cable end in a clamping or connecting device.

A further object is to provide an improved jig, embodying means for accurately determining and fixing the position of a cable holding member along a conductor, preparatory to securing of the holding member to the conductor.

A still further object is to provide a jig for use in preparing cable-ends, the jig being so dimensioned, that when employed with a cable end, it will provide positive assurance that the prepared portion of the cable will be perfectly adapted for the apparatus with which it is to be connected or used.

Additional objects will appear from the drawings and the following detailed description.

It will, of course, be understood that the present description and the accompanying drawings relate to a single, preferred executive embodiment of the present invention, and that substantial changes in the described construction, arrangement and adaptability of the detailed parts, may be made without departing from the spirit and scope of the invention.

The preferred form of jig hereinafter described, is particularly adapted for the preparation of cable ends to be inserted into a connecting device such as is described in my co-pending application, filed January 16, 1929, and bearing Serial No. 332,942.

Referring to the drawings, Fig. 1 is a side elevation, partially in section, of a preferred form of jig, made according to the present invention; Fig. 2 is a sectional elevation of a conductor end, previously prepared by the jig shown in Fig. 1, and secured in place, in a connecting device.

Referring by numerals to the drawings, the

tool 10 may be constructed in any suitable manner, depending upon the characteristics of the conductor to be prepared thereby, and upon the nature of its service connection. By way of illustration, the jig is shown as 55 comprising a body portion which is substantially cylindrical in shape, and hollow substantially over its length, and having one end 11 threaded to form attachment means for a sleeve or nut 12. The opposite end of the 60 hollow body portion is partially closed to form an internal abutment 13. A projecting lug 14 is externally disposed on one end of the body, preferably in radial alignment with the abutment 13. The lug 14 is disposed in 65 definitely spaced relation to a knife-edge member 15, which is threadedly, or otherwise removably attached to the body portion of the jig 10. The member 15 constitutes a 70 scribe, or marking element, and may be proportioned to serve as a cutting element for the cable sheath. A shoulder 16 is provided on the lug 14, to form a seat or stop for the cable placed thereon. The distance between the shoulder 16 and the knife edge, is preferably 75 determined by, and substantially equal to, the length of a clamping groove 17, or a like attaching seat, in which the stripped cable end is ultimately to be located, when in service. Therefore, by placing the end of a cable 80 substantially parallel to the jig body, against the shoulder 16 of the lug 14, and upon rotating the jig with the cable in contact with the knife edge 15, the necessary length of bare 85 cable will be marked thereon; if this operation be continued, and the member 15 be employed as a cutting element, the cutting edge thereof will serve to sever the insulation to the required depth, to enable its easy removal, 90 and thus to leave the required length of bare cable end. At the same operation, the length of removal of lead sheath 18 down to the insulating material 19, may be determined by marking the cable at a point corresponding 95 substantially to the end 20 of the jig 10.

After completion of the stripping operations, the cable is ready for insertion into the jig. The cable is extended into the bore of the jig, from the threaded end thereof, to a 100

point where the bare end of the cable abuts the shoulder 13. The shoulder 21, formed on the cable by the removal of the insulation, at the same time impinges upon a shoulder 22 5 formed in the jig, these relations being observed through a sight hole 23 formed in the jig body, before clamping the conductor in place by a set wrench 24. It will be readily seen that the relation of parts of the jig and 10 cable, as just described, are all predetermined by the relative positions of the parts 14 and 15 on the outside of the jig body. A holding member 25, associated with the nut 12, may then be positioned along the conductor, by 15 securing of the nut to the threaded end 11 of the jig, and in this position the cable may be wiped or soldered, as shown at 26, into engagement with the end of the sleeve.

By way of illustration, the nut 12 and the 20 holding member 25 have been described as cooperating with the jig 10, as parts thereof. It will, however, be seen that these parts constitute means for attaching a cable to an insulated cable-clamping or connecting device, 25 such as is illustrated in Fig. 2; and that the length of the body portion of the jig, is, in the present example, equal to, and determined by the length of the cable to be inserted in the connecting device (of Fig. 2) as a whole, exclusive of the parts 12 and 25.

Obviously, any of the many equivalents of the holding member 25 and nut 12 may be employed and, instead of using the described threaded connection on member 12, this element may be frictionally retained, keyed or pinned to the jig body while effecting the soldering or wiping operations.

By way of illustration of a single application of the described jig, it may be indicated that the clamping groove 17 (of Fig. 40 2) is formed in a suitable cable clamp 27 for interconnecting a plurality of cable ends; and that the conductor is housed in a metal container, a wall portion thereof being indicated at 28, and the conductor insulated from the wall portion by an insulating body 29. An entrance nipple 30 and an insulating bushing 31 aid, respectively, in positioning and insulating the cable entering the container 28.

Particularly in a cable-clamping and connecting device of the sort referred to above, and described in the copending application hereof noted, it is desirable that a cable 55 end be stripped to no greater length than necessary, and that a holding member such as 25, be accurately located along the cable. It will be seen that the described jig or tool precludes inaccuracies in locating such a holding member, results in uniform stripping, and effects a substantial saving of time in the complete process of preparing cable ends.

I claim as my invention:

1. In a tool for preparing an insulated

conductor for securement to a holding member having a threaded portion, an element for receiving an end portion of the conductor, a threaded portion on said element adapted to position the holding member with respect thereto, and combined gauge and stripping means carried by said element.

2. A combined gauge and holding tool for receiving and preparing a metal-sheath cable for electrical connection and connection with a cable sleeve including a sleeve holding portion, a stripping gauge, and means for removably securing the tool to the cable.

3. In a tool for preparing an insulated conductor for electrical connection and securement to a threaded cable sleeve, a body portion of tubular form adapted to receive an end portion of the conductor, gauge means carried exteriorly of the body, and adapted for fixing the location of the sleeve along the conductor, and threaded means formed on the body portion, for detachable engagement with the cable sleeve.

4. A tool for preparing an insulated conductor for electrical connection, and for securement to a holding member distinct from said connection, said tool including a gauge determining the extent of insulation to be removed, a body having a longitudinal channel for receiving the conductor, means carried by the body, for positioning and holding the tool with respect to the conductor, and means on the body for detachably engaging the holding member to fix its position along the conductor.

5. In a tool for preparing insulated cable for electrical connection with a device employing an exterior cable support, and for holding the cable during securement to said support, a body having a longitudinal cable channel, means on the body for gauging the distance between said support and a stripped cable portion, combined means carried by the body, for gauging the length of cable to be stripped, and severing the insulation therefrom, and a portion on said body for detachably engaging the cable support.

6. In a tool for preparing metal sheath cable for connection with enclosed electrical apparatus employing an exterior cable-sleeve, a tubular body portion, means forming a stripping-gauge on said body, stops carried internally of said body, for determining the length of insulated cable to extend within the enclosure for associated apparatus, and a sleeve-holding portion, carried exteriorly of the body.

7. In a tool for preparing metal-sheath cable for connection into a junction box, or the like, employing an exterior, threaded, cable-holding sleeve, a tubular body constituting a receiver for the cable end; means forming, on the body, a gauge determining

the length of cable to be stripped, and a cutting element for the insulation; a clamp for the cable end, associated with the receiver, and screw-threaded means on the body, for securement of the tool to the cable holding sleeve, and adapted to determine the position of such sleeve, along the conductor.
